UNITED STATES PATENT OFFICE.

ALVA E. DOWELL, OF MACOMB, ILLINOIS.

INDOOR TOILET.

1,363,459.

Specification of Letters Patent. Patented Dec. 28, 1920.

Application filed February 9, 1920. Serial No. 357,476.

To all whom it may concern:

Be it known that I, ALVA E. DOWELL, a citizen of the United States, a resident of Macomb, in the county of McDonough and 5 State of Illinois, have invented new and useful Improvements in Indoor Toilets, of which the following is a specification.

This invention has reference to indoor toilets, and it has for its principal object, to 10 improve devices of this character to the extent that all repugnant and noxious odors and gases are carried away by a new arrangement of vents connected to a suitable flue.

15 I am aware that various ventilating appliances have been applied to indoor toilets of the character herein referred to, and that in connection therewith, chemical mixtures are employed to throw down the noxious 20 odors and gases, supplemented by the use of the ventilating means, but I have found that odorous gases accumulate, not only in the cabinet beneath the seat, but more especially around the seat opening, beneath 25 the cover or top and out of the natural path of travel of the gases to the usual vent, as they rise in the cabinet. And it is in the arrangement of an improved vent in which my invention resides that I am to improve 30 devices of this character by carrying off all odors and gases not suppressed by the chemical mixture. With my improved vent, I also obviate any chance of noxious gases 35 escaping into the dwelling and endangering the lives of the occupants, when the cover or top is closed.

In the drawings,—

Figure 1 is a vertical sectional elevation of an indoor toilet embodying my invention; 40 Fig. 2 is a plan view, partly in section, as the same would appear, if taken on the line 2—2, Fig. 1.

Like characters of reference denote corresponding parts throughout the figures.

45 The cabinet, which may be of the usual construction, is designated 1, provided with the ventilating chamber 2, to which is connected the vertical vent pipe 3, which may lead out through the roof of a dwelling or be 50 connected to a house flue having communication with the outside of the dwelling. The usual container 4 is shown within the cabinet having the bail-handle 5 for removing and placing the container in the cabinet.

55 The top of the cabinet is covered by a seat which includes a part 6 hinged at 7 to a part

8. The part 6 is arranged to be raised and lowered to permit an attendant to remove the container 4. The part 6 is also provided with the usual seat opening 9. 60

Adapted to cover the seat opening 9 is a cover or top 10, which is pivotally connected to the device to permit it to be swung away from and toward the seat so as to uncover and cover the seat opening 9, as of course 65 will be understood. In the particular arrangement of the cover or top 10 shown, it is not intended to raise or lower it, as could be the case, but to swing it away from and toward the seat, in a horizontal plane. To 70 accomplish this, I connect the cover or top 10 with an arm or bracket 11 having a swingable connection, preferably with the vent pipe leading from the cabinet.

Coming now to my improved ventilating 75 means, which acts supplementary to the customary ventilating means on devices of this character, 12 designates a vent pipe connected at one end to the cover or top 10 and communicating with the interior of 80 the cabinet 1, when the cover or top 10 is over the seat opening 9, through an opening 13 in said cover or top 10. The other end of the vent pipe 12 has a swingable connection with the vent pipe 3 leading from the 85 cabinet, and communicates with the interior of said last mentioned pipe through an opening, 14 therein, see Fig. 1. It will be observed that when the cover or top 10 and vent 12 are swung out and away from the 90 seat of the cabinet, that the opening 14 in the vent pipe 3 is closed and escaping gases may not be deflected back through the vent pipe 12 and into the dwelling, but that when the parts have been swung into the position 95 shown in Fig. 1, the ventilating chamber 2 and vent pipe 3 supplemented by the vent pipe 12 will carry away all repugnant and noxious odors and gases from and within the cabinet and all of its crevices and pock- 100 ets keep the same in a clean and sanitary condition.

What I claim is:

1. In an indoor toilet, in combination with the cabinet and vent pipe leading therefrom, a movable cover for the seat opening, and a vent connected to the cover and vent pipe adapted to have communication with the interior of the cabinet and with the vent pipe. 105

2. In an indoor toilet, in combination with the cabinet and vent pipe leading therefrom,

said vent pipe having an exit opening above the cabinet, a movable cover for the seat opening having an exit opening therein, and a vent providing communication from 5 the opening in the cover to the opening in said pipe.

3. In an indoor toilet, in combination with the cabinet and vent pipe leading therefrom, said vent pipe having an exit opening above the cabinet, a cover for the 10 seat opening having an exit opening therein,

means for swingably connecting said cover with the vent pipe leading from the cabinet, and a communicating vent between said exit openings in the cover and said pipe, so arranged that when the cover is swung to uncover the seat opening, to close the exit opening in said pipe.

In witness whereof, I have hereunto affixed my hand this 19th day of January, 1920.

ALVA E. DOWELL.
